UNITED STATES PATENT OFFICE

THOMAS TORIO, OF CORONA, NEW YORK

SHOE

Application filed August 4, 1931. Serial No. 555,037.

This invention relates essentially to a shoe of the kind in which the upper is sewed to the inner sole by means of a curved stitch entering a split portion of the sole. The invention is designed to provide an inner sole which is split along its perimeter from the heel to the toe so that the upper can be suitably shaped over the edge of the split member and conveniently sewed without piercing the ⁵ side of the sole.

In the construction of shoes and more particularly ladies' shoes, it is very desirable that the instep or apex of the arch should be as narrow as possible so as to provide a shoe ¹⁰ of graceful appearance.

This is accomplished in the present invention by splitting the sole at the instep as closely as possible to the center so as to allow sufficient material for stitching and sewing ²⁰ the upper.

The split arrangement of the inner sole also provides the construction of a pocket at the arch, thereby forming means for housing a stiffener or arch supporter, which is ²⁵ cemented or otherwise rigidly fastened in the pocket.

The invention resides more particularly in the novel combinations hereinafter described and claimed, reference being made to the accompanying drawing in which:

Fig. 1 represents a sectional side elevation of a shoe embodying this invention.

Fig. 2 is a plan view of the inner sole.

Fig. 3 is a transverse section showing the ³⁵ inner sole stitched to the upper.

Fig. 4 is a transverse section taken along the line 4-4 of Fig. 1.

Fig. 5 is a transverse section of the inner sole.

In the drawing the numeral 4 designates an inner sole which is provided with a split portion 5 located at its edge from the toe to the heel. The lower part of the split member is turned downwardly, forming a flap 6 for ⁴⁰ positioning the material of the upper 7, which is curved around the upper portion of the split member. The lower portion of the split member is bent downwardly and the end of the upper is sewed to the bent portion with its ⁴⁵ body stretched over the edge of the upper ⁵⁰

part of the split member. The upper can be sewed to the flap by means of a stitch 8 entering the outer part of the upper and piercing the outer surface of the flap, as shown in Fig. 3. In a shoe made like the foregoing, the sewing does not pierce the inside of the sole, thus insuring a smooth surface for the support of the foot. The invention supplies an easy method of sewing, stapling or otherwise securing the upper to the flap thereby ⁵⁵ avoiding the use of a welt or any special sewing machine.

As indicated in Fig. 4, the rear portion of the split member constitutes a pocket 9 to position a steel shank or arch member 10 ⁶⁰ which may be cemented or otherwise fastened in the pocket. After the shank member is located in the pocket the flaps and the upper are flattened or straightened out to fit over the surface of the shank.

An outer sole 11 is arranged under the upper and it entirely covers the seam thereof. The outer sole can be cemented to the upper or secured in any well-known manner to the upper and inner sole.

I claim:

A shoe construction comprising an inner sole having a split perimeter from the toe to the heel thereof, the lower part of said split portion being folded downwardly and inwardly with the free ends thereof opposing each other, an upper secured to the outer part of said downwardly bent portion, the under part of said sole and the downwardly and inwardly bent ends of said portion cooperating to form adjacent the arch a pocket completely enclosed at its sides and a sole shank stiffener located in said pocket.

In testimony whereof I have hereunto set my hand.

THOMAS TORIO.
